US00D607403S

(12) **United States Design Patent**
Hara et al.

(10) **Patent No.:** US D607,403 S
(45) **Date of Patent:** ** Jan. 5, 2010

(54) **CHARGER**

(75) Inventors: **Tomomi Hara**, Osaka (JP); **Seiichi Kato**, Osaka (JP)

(73) Assignee: **Panasonic Corporation**, Osaka (JP)

(**) Term: **14 Years**

(21) Appl. No.: **29/335,162**

(22) Filed: **Apr. 9, 2009**

(30) **Foreign Application Priority Data**

Oct. 10, 2008 (JP) 2008-026297

(51) **LOC (9) Cl.** 13-02

(52) **U.S. Cl.** D13/107

(58) **Field of Classification Search** D13/102–103, D13/107–110, 118–119, 133, 144, 184; D14/251, D14/253, 432, 434, 184; 439/300, 620, 638, 439/668–669, 675, 825; 320/107–115; 363/146; D19/92

See application file for complete search history.

JP Office Action mailed Aug. 4, 2009 in the counterpart JP application.

Primary Examiner—Rosemary K Tarcza

(74) Attorney, Agent, or Firm—Brinks Hofer Gilson & Lione

(57) **CLAIM**

we claim the ornamental design for a charger, as shown and described.

DESCRIPTION

FIG. 1 is a front and right side perspective view of a charger of the present invention;

FIG. 2 is a front and left side perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken line showing of charger is included for the purpose of illustrating environment and forms no part of the claimed design.

1 Claim, 8 Drawing Sheets
